SPRAY GUN FOR COATING THE INTERIOR
OF CONDUITS

John C. Carnevale, Menlo Park, Calif.

Application January 5, 1945, Serial No. 571,487

4 Claims. (Cl. 91—44)

(Granted under the act of March 3, 1883, as
amended April 30, 1928; 370 O. G. 757)

1

This invention relates to a device for applying a protective coating, and more specifically, to a device with which a protective coating may progressively be applied to the inside surface of hollow bodies, such as conduits.

Ships, and in particular, navy ships, are equipped with a system of main and auxiliary piping for conveying salt water to the various parts of the ship for fire control and other purposes. The piping and conduits which are employed in such systems are internally coated with protective compositions to prevent undue corrosion from the sea water. Heretofore, the coating has been applied by removing the pipes and conduits, section by section, from the ship and submerging each section in a bath of the coating composition, removing it, hanging it up to drain, allowing it to dry, and then reinstalling it in the ship. There are disadvantages incident to such procedure, namely, the necessity, of tying up the ship for a considerable period, of removing all the piping and valves connected thereto which involves considerable labor and time, a waste of the coating composition and damage to the coated surface of the conduit during reinstallation.

It is an object of this invention to provide means with which the inside surface of hollow bodies, specifically piping and conduits, may be coated with a protective composition in situ, which will be effective in straight or angular piping, which will be inexpensive and easy to operate.

As illustrated herein, invention resides in means movable lengthwise of a hollow member adapted to emit a diffused cloud of a coating material from substantially a point source, substantially at the longitudinal axis of the hollow member, radially outward, and supporting means for automatically maintaining the aforesaid means concomitant with the longitudinal axis of the hollow member. More specifically, in one form the aforesaid means comprise an articulated body having a nozzle attached to one end and a supply conduit attached to the opposite end, the articulated sections of the body having attached thereto, radially disposed adjustable arms adapted to support the articulated body in concentric relation with respect to the hollow body, and anti-friction rollers at the ends of the arms adapted to engage the inside surface of the hollow body, and thereby to facilitate movement of the device longitudinally. In another form of the invention, there is associated with the first mentioned means, supporting means consisting of elongated members having anti-friction rollers at

2

their opposite ends, means for connecting said elongated members to said first named means, means adjustable longitudinally of the hollow body to expand the connecting means radially, and yieldable means opposing the expansion of said connecting means.

The invention will now be described in detail with reference to the accompanying drawings, in which:

10 Fig. 1 is a plan view of the spray coating device which forms the subject matter of the present invention;

15 Fig. 2 is a perspective view of the spray coating device as seen looking at the nozzle end thereof;

Fig. 3 is a front view looking directly at the nozzle;

Fig. 4 is a plan view showing the articulated parts thereof at an angle with respect to each other as would be the case when the device was forced around a bend in the conduit being coated;

Fig. 5 is a longitudinal section through a modified form of the spray coating device;

25 Fig. 6 shows a section on the line 6—6 of Fig. 5 looking from the nozzle rearwardly and illustrating the position of the device inside of a conduit C; and

Fig. 7 is a modified form of the invention shown in Fig. 5 in which each conduit contacting shoe is provided at its opposite ends with anti-friction devices.

Referring to the drawing, the spray coating device for coating the inside of conduits and piping is represented generally by the reference character 10 and consists of a spray nozzle 12, adapted to eject a diffused cloud of coating composition radially outward and which is supported centrally of a conduit C such as that shown in Fig. 3 by radially disposed arms 14 and 16 arranged as will be related hereinafter. The nozzle 12, which is of standard construction and adjustable to give a suitable spray of coating material, is threaded onto one end of a hollow body 18 and to the opposite end of this hollow body is threaded a hollow handle 20 through which air and the coating composition are introduced to the hollow body 18 and the nozzle 12. The hollow handle 20 has at its free end a threaded portion over which may be clamped a flexible supply conduit (not shown) for conducting the coating composition from high pressure supply receptacles. A pair of discs 22 and 24 are mounted on the body 18, preferably threaded

thereon, and their position is fixed by means of nuts 26 and 28 also threaded on the body 18 against the discs 22 and 24, respectively. Each of the aforesaid radial arms 14 is provided with a slot 30 and each of the radial arms 16 is provided with a slot 32. Through these slots are passed screws 34 and 36, respectively, the screws being threaded into the discs 22 and 24 and serving to hold the arms 14 and 16 rigidly clamped against one face of the disc. By slackening off on the screws 34 and 36, the arms may be adjusted inwardly or outwardly relative to the discs to provide for adjusting the spray coating device so that it has a freely sliding fit in the conduit to be coated. Each of the arms 14 has at its terminal end a forwardly projecting portion 38 which is bifurcated to receive a disc 40 journaled for rotation therein. In like manner, each of the arms 16 is provided with both forwardly and rearwardly projecting portions 42, the opposite terminal ends of which are bifurcated for the reception of discs 44 which are journaled therein. The discs 40 and 44 at the ends of the respective arms are adapted to bear against the inside surface of the conduit to which a coating is to be applied, and to facilitate movement of the spray coating device through the conduit. In order to reduce the frictional contact between the discs and the wall of the conduit and thereby to increase mobility of the spray coating device as much as possible, the discs 40 and 44 are provided with a sharp peripheral edge which affords substantially line contact between them and the inner surface of the conduit. The adjustment of each arm 14 is limited only by the length of the slot 30. The adjustment of the arms 16 inwardly, however, is limited by the periphery of the disc 24 since the forwardly and rearwardly projecting portion 42 will engage the periphery of the disc 24 when the arms 16 are moved inwardly. To permit the arm 16 to be adjusted inwardly to the same extent as the arms 14, slots or notches 48 are formed in the disc 24 of such width as to accommodate the portion 42. It may also be necessary to notch the portion 42 at 48 if the portion 42 is not of uniform thickness throughout. In order that the spray coating device may be useful not only in straight conduits, but also in conduits having bends therein, the body 18 of the spray coating device is articulated, the articulation being provided for by a ball 50 and socket 52. This arrangement permits substantially universal movement between the fore part of the coating device which carries the nozzle 12 and the rear part of the device which includes the handle 20. Slots 54 are formed in the socket 52 to accommodate the members 42 at the limit of their inner adjustment.

The modified form of the invention, shown in Fig. 5, and denoted generally by the reference character 58, comprises a nozzle 60 threaded onto one end of a hollow body 62 to the opposite end of which is threaded a nipple 64 adapted to be connected to a flexible conduit (not shown) for conducting the coating material and air to the nozzle. Formed integral with the body 62 adjacent to the nozzle 60 are three radially disposed lugs 66. At the opposite end near the nipple 64, there is a sleeve 68 threaded on the body 62, the sleeve having telescopically disposed thereon, a collar 70. The lugs 66 and the collar 70 are provided with bearing posts 72 and 74 having extending therethrough from opposite sides, pins 73 and 75. On the opposite ends of

the pins 73 and 75 are journaled arms 76, which extend inwardly toward each other and are pivoted on the opposite ends of pins 77 and 79 fixed transversely in posts 78, the latter being formed integral with shoes 80 having substantially convex surfaces adapted, as shown in Fig. 6, to bear against the inner surface of a conduit C. The shoes 80 being equidistant from each other form a three point support for the spray device within the conduit, and hence, hold it centrally thereof. Between the legs 66 and the sleeve 68 there is disposed a washer 82 and a spring 84, the latter bearing at one end against the lugs 66 and at its opposite end against the washer 82, by its force opposing movement of the sleeve 68 toward the lugs 66. The sleeve 68 is provided with an enlarged knurled head 86, by which the sleeve may be rotated to move it longitudinally on the body 62 toward or away from the lugs 66, thereby to expand or contract the shoes 80 with respect to the body 62. It is evident that by this construction the radial position of the shoes may be changed to accommodate whatever diameter of conduits is to be coated. While the aforesaid shoes 80 are provided with smooth convex surfaces which permits the device to slide through the conduit C, if the conduit is of considerable length, it is desirable to reduce the friction between the device and the inner surfaces of the conduit and this may be done as illustrated in Fig. 7 by bifurcating the opposite ends of the shoes and journaling discs 88 therein, similar to the disc 40 described in the form of the invention shown in Fig. 1.

Preparatory to using the device shown in either of its forms, the operator adjusts the radial arms 14 and 16 or the sleeve 68 so that the rollers 40 and 44 or the shoes 80 freely fit the inside diameter of the conduit which is to be coated. The supply line is then connected to the handle 20 or to the nipple 64, and the coating material together with air for forcing it through the nozzle is permitted to enter the device. The character of the spray coating material which is to be applied to the inside surface of the conduit, will be determined by adjustment of the spray nozzle 12 in the usual manner, and since such adjustment of a nozzle is common in practice, it will not be described herein. The device is then pushed through the conduit slowly and the coating material will be applied evenly and uniformly over the entire inner surface of the conduit by reason of the fact that the rollers 40 and 44 or the shoes 80 hold the spray nozzle 12 centrally of the conduit. Where the conduit has bends in it, it is necessary to use the form of the invention shown in Fig. 1, and also where the conduit is of great length. In short straight conduits, the form of the invention shown in Fig. 5 may satisfactorily be employed, however, if this is to be used for great lengths of conduit its movement through the conduit may greatly be facilitated by use of the discs 88, as shown in Fig. 7. It is evident that by using the device described in its various forms, the coating may be carried out without removing the piping from the ships, and hence the coating operation may be performed without dismantling the entire piping system and at a minimum loss in time.

The invention described herein may be manufactured and used by or for the Government of the United States of America for governmental purposes without the payment of any royalties thereon or therefor.

What is claimed is:

1. A device for coating the inside surface of an elongated hollow member, comprising means movable lengthwise of the hollow member adapted to emit a diffused spray of coating composition from a substantially point source, substantially at the longitudinal axis of said hollow member, radially outward, an articulated support for said means, each portion of said articulated support having radially disposed adjustable arms extending therefrom adapted to bear against the inner surface of the walls of said hollow member and to hold said means concentric with respect thereto.

2. A device for coating the inside surface of an elongated hollow member, comprising means movable lengthwise of the hollow member adapted to emit a diffused spray of coating composition from a substantially point source, substantially at the longitudinal axis of the hollow member radially outward, a two part articulated support, one part of which is universally movable with respect to the other, radial arms extending from each part, and anti-friction discs at the ends of said arms.

3. A device for coating the inside surface of an elongated hollow member, comprising means movable lengthwise of the hollow member adapted to emit a diffused spray of coating composition from a substantially point source, substantially at the longitudinal axis of the hollow member, radially outward, a two part articulated support, the parts of which are universally movable relative to each other, radially disposed arms extending from each part, the radial arms of

one part terminating in single point wall contacting means and the radial arms of the other part terminating in two point walls contacting means.

5 4. A device for coating the inside surface of an elongated hollow member, comprising means movable lengthwise of the hollow member adapted to emit a diffused spray of coating composition from a substantially point source, substantially at the longitudinal axis of the hollow member, radially outward, said means comprising a length of pipe, a spray nozzle fixed to one end thereof, a conduit fixed to the other end thereof, said length of pipe being articulated between its ends to provide elements universally movable with respect to each other, a circular plate threaded onto each element of the pipe, a plurality of arms, means for adjustably fastening each arm to the circular plate for movement with respect thereto in a direction substantially normal to a radial line extending through said fastening means, and anti-friction rolls at the terminal ends of said arms.
